JONAS KENDALL, OF SOUTH FRAMINGHAM, AND ADDISON HATHAWAY, OF LENOX,
ASSIGNORS TO ANDREW T. SERVEN, OF LENOX, MASSACHUSETTS.

Letters Patent No. 79,131, dated June 23, 1868.

IMPROVED MACHINE FOR GRINDING GLASS PLATES, &c.

The Schedule referred to in these Letters Patent and making part of the same.

TO ALL WHOM IT MAY CONCERN:

Be it known that we, JONAS KENDALL, of South Framingham, Middlesex county, and ADDISON HATHAWAY, of Lenox, Berkshire county, all in the State of Massachusetts, have invented an Improvement in Machines for Grinding Glass Plates, &c.; and we do hereby declare that the following, taken in connection with the drawings which accompany and form part of this specification, is a description of our invention sufficient to enable those skilled in the art to practise it.

Our invention relates particularly to an organization of mechanism for grinding or reducing the surfaces of glass plates, the invention being particularly designed for bringing the surfaces of such plates to perfectly uniform planes.

In carrying out our invention, we employ a reciprocating carriage or table for holding the plate to be ground, and a series of circular grinding-disks, the disks having a rotary motion about a central common axis; and our invention consists, primarily, in imparting to each of these grinding-disks a positive rotary motion on its own axis.

The drawings represent a machine embodying our improvements.

A shows the same in end elevation.

B is a side elevation thereof.

C, a plan.

a denotes a frame, having ways, *b*, upon which is mounted a sliding carriage, *c*, the upper surface of which forms the table upon which the plate of glass to be worked is placed and confined for the action of the grinding-mechanism.

This carriage has a gear-rack, into which meshes a gear on shaft, *d*, rotation of the shaft in alternate directions effecting reciprocating horizontal movements of the carriage.

Over the table *c*, between uprights *e*, is a frame, *f*, having bearings, in which is mounted a vertical shaft, *h*. On the lower end of this shaft is fixed a wheel, *i*, carrying a series of grinding-disks or tools, *k*, each supported on the lower end of a vertical shaft, *l*, rotating in a bearing on the wheel *i*.

The wheel *i* has a rotary motion imparted to it through the shaft *h*; (by means of a gear, *m*, on a shaft, *n*, meshing into and driving a gear, *o*, on the shaft *h*, or in any other suitable manner,) and this rotary motion of the wheel, as will be readily seen, gives a movement to each grinding-disk across the face of the reciprocating plate, traversing to and fro beneath the grinders, with and upon the reciprocating table.

We have found in practice, however, that the rotary motion imparted to each disk by friction, under the compound traversing motion of the plate and rotary motion of the wheel, is unreliable, in that, under slight obstructions, the disks remain stationary relatively to the wheel, and that the plate is thus prevented from being uniformly reduced, scratches being also often made upon the surface being ground. These difficulties we find we can overcome by giving to each disk, as it revolves around the axis *h*, a positive rotary motion on its own axis, and to effect this we fix on the top of each shaft *l* a gear-pinion, *p*, the several pinions *p* meshing into the teeth of a stationary gear, *q*, fixed to the frame *f*, the rotation of the pinions around this gear effecting the rotation of each on its own axis, and the consequent rotation of the grinding-disk on its axis.

It will be obvious that this will overcome any tendency of any disk to scratch or to work irregularly on the surface of the plate beneath it.

Where the motion of the disks is not thus made positive, each disk is apt to get sprung from its horizontality, as it passes upon and off from the end of a plate, and if this horizontality is not kept up, the disk will soon maintain a fixed position relatively to the wheel, or will fail to be rotated by friction against the plate, and will consequently fail to grind the glass surface down to a perfect plane.

Gearing the grinding-disks, as shown, causes every part of the disk to act uniformly, the surface of the glass being subjected to the compound motion of the table on its ways, the motion of each disk across its surface, and the motion of each disk on its axis, and plates thus ground are found to present fewer defects than those ground in any other manner.

The opposite ends of the frame f are sustained in grooves in the uprights e , and the frame is made capable of vertical movement in these grooves, to feed the grinding-disks down as they reduce or wear away the surface of the glass.

The frame is hung on screws, r , working in threads in the top rail s of the frame, the screw-shafts being mounted in a cross-piece, t , and bearing, at their upper ends, bevel-gears u , driven by pinions v on a cross-shaft, w .

To impart an automatic downward movement to the grinders, at the end of each movement of the carriage e , and in connection with the shipping-mechanism for effecting alternate movements of the carriage, by changing the direction of motion of the shaft at the end of each forward or back movement of the carriage, a mechanism is employed, as follows:

The shaft w has at one end a gear, x , which meshes into and is driven by a gear, y , on top of a shaft, z , the lower end of shaft z having a gear, a^2 , driven by a gear, b^2 , on a shaft, c^2 . Shaft c^2 carries a ratchet-wheel, d^2 , into the teeth of which engages a pawl, e^2 . This pawl is connected to and is actuated by a lever, f^2 , hung on a fulcrum, g^2 , and having an arm, h^2 , extending in towards the carriage e , as shown at A and C. On the edge of the carriage e , in line with this arm, are two inclines, i^2 , and as the movement of the carriage in either direction is terminating, one of these inclines passes under the arm h^2 , and, by raising it, depresses the opposite end of the lever, thereby forcing down the pawl e^2 , (which is held against the ratchet by a suitable spring,) and turning the ratchet, the movement of the ratchet communicating motion (through the train of gearing just described) to the frame f , and thereby gradually letting down the grinding-disks as the reduction of the surface of the plate progresses. The ratchet-pawl is returned to its normal position, after the incline passes from it, by a suitable spring, r^2 . The shaft e^2 carries a hand-wheel, j^2 , by rotation of which the grinders may be raised and lowered in introducing the glass and setting the machine to work, or in removing the glass.

Adjacent to each incline i^2 is a dog, k^2 , which, as the carriage is completing its movement, strikes an arm, l^2 , of a lever, m^2 , the opposite end of which is jointed to an arm, n^2 , of a shipper-fork, o^2 , the movement of the lever m^2 , in either direction, by either dog, k^2 , shifting the belts, and thereby changing the direction of motion of the carriage, this change taking place simultaneously with or immediately subsequent to the downward movement of the grinding-disks, as above described.

We claim, in combination with the series of disks or grinders, rotating around a common axis and over a reciprocating table, giving to each disk or grinder a positive rotary motion on its own axis, substantially as described.

We also claim, in combination with the rotary grinding-disks, the mechanism for automatically effecting their downward movement as the grinding progresses, substantially as described.

JONAS KENDALL,
ADDISON HATHAWAY.
